UNITED STATES PATENT OFFICE.

JAMES PATTERSON, OF WILLIAMSTOWN, WEST VIRGINIA, AND MICHAEL B. CARMODY, OF MARIETTA, OHIO.

SCREENING DEVICE FOR FLUIDS.

SPECIFICATION forming part of Letters Patent No. 549,390, dated November 5, 1895.

Application filed December 24, 1894. Serial No. 532,828. (No model.)

To all whom it may concern:

Be it known that we, JAMES PATTERSON, of Williamstown, in the county of Wood and State of West Virginia, and MICHAEL B. CARMODY, of Marietta, in the county of Washington and State of Ohio, have invented a new and Improved Screening Device for Fluids, of which the following is a full, clear, and exact description.

10. The invention relates to screens used in pipes or mains for conducting natural gas, water, oil, and other fluids.

The object of the invention is to provide a new and improved screening device which is 15 comparatively simple and durable in construction, very effective in operation, arranged to intercept solid matter and other impurities, and to permit of conveniently removing the same from time to time, as required.

The invention consists principally of a screen arranged in the path of the fluid and at an angle to its flow.

The invention also consists of certain parts 25 and details and combinations of the same, as will be fully described hereinafter, and then pointed out in the claims.

Reference is to be had to the accompanying drawing, forming a part of this specification, 30 in which the figure is a sectional side elevation of the improvement.

The improved screening device is provided with a casing A, of cylindrical, spherical, or other form, and through which flows the fluid 35 in the direction of the arrow a', the said casing being arranged in a main pipe or other conductor B, as is illustrated in the drawing.

In the casing A is arranged a screen C, standing approximately at an angle of about 40 forty-five degrees to the flow of the fluid passing through the casing, and this screen C is preferably supported on suitable transverse bars D to hold the screen in a comparatively straight position. The screen is introduced 45 into the casing A through an opening A', formed in the top of the casing A, and on the upper end of the screen is secured a transverse bar E, extending into the enlarged portion A² of the opening A' to rest on the 50 shoulders formed in the casing A. The outer

end of the opening A' is adapted to be closed by a suitable cap F, bolted or otherwise fastened to the casing A, and when removed permits of withdrawing the screen C from the casing for repairs, for replacing, or for other purposes, as the case may be. On the bar E is formed a hook E' for conveniently removing the screen whenever desired. The lower end of the screen C extends into a transverse slot A³, formed on the inside of the casing, as 60 indicated in the drawing. The lower part of the screen C discharges into a recess A⁴, formed in the bottom of the casing A and provided with a draw-off cock G for removing or drawing off the accumulated solid matter 65 or impurities from time to time. At the top of the recess A⁴ is arranged a horizontally-disposed screen H, secured in place by screws or other means and terminating at its free and slightly downwardly-curved end a suitable 70 distance from the lower end of the screen C to form a passage I for the solid matter or other impurities intercepted by the screen C.

Now it will be seen that solid matter or other impurities contained in the liquid flowing through the casing are not capable of passing through the meshes of the screen, as they are intercepted by the latter and roll down the screen to pass through the passage I into the recess A⁴, in which they accumulate 75 and are retained by the screen H, to be drawn off from time to time.

Now it will be seen that by setting the screen at an angle to the flow of the fluid the solid matter is intercepted and discharged at 80 the bottom, as described, and at the same time a large screening-surface is presented to the fluid. Furthermore, the screen may be easily removed for cleaning or other purposes.

Having thus fully described our invention, 85 we claim as new and desire to secure by Letters Patent—

1. A screening device for fluids, comprising a casing formed with an opening in the top having an outer enlarged portion and a transverse recess formed in the inside of the bottom of said casing, a screen held removably in the casing and fitting at its lower end in the said transverse recess, and a transverse bar secured to the top of said screen and held 95

in the enlarged portion of the opening in the top of the casing, substantially as shown and described.

2. A screening device for fluids, comprising 5 a casing formed with an opening in its top having an outer enlarged portion, a screen held removably in the said casing, transverse bars arranged in said casing to support the said screen, a transverse bar secured to the 10 upper end of the screen and adapted to rest in the enlarged portion of the opening and means for closing the outer end of the opening, substantially as described.

3. A screening device for fluids, comprising 15 a casing formed with a recess for receiving collected impurities and other matter, the said casing being provided with an opening in its top having an outer enlarged portion, the inner surface of the casing at the bottom

being provided with a transverse groove, a screen held removably in the said casing and fitting with its lower end in the said transverse groove, the upper end of the screen being provided with a bar adapted to rest in the enlarged portion of the opening, the said screen being arranged at an angle to the flow of the liquid, and a second screen secured to the casing and arranged over part of the said recess and terminating a suitable distance from the inclined screen to form a passage leading 30 into the said recess, substantially as shown and described.
